Patented Aug. 21, 1917.

UNITED STATES PATENT OFFICE.

ANDREW A. MCINTYRE, OF CAMDEN, NEW JERSEY, ASSIGNEE TO JOHN L. YOUNG, OF PHILADELPHIA, PENNSYLVANIA.

HEEL-BREASTING MECHANISM.

1,237,925.

Specification of Letters Patent. Patented Aug. 21, 1917.

Application filed March 1, 1916. Serial No. 81,407.

To all whom it may concern:

Be it known that I, ANDREW A. MCINTYRE, a citizen of the United States, residing at Camden, in the county of Camden and State of New Jersey, have invented certain new and useful Improvements in Heel-Breasting Mechanism, of which the following is a specification.

This invention relates, broadly stated, to heel breeding mechanism and has more particular relation to the providing of a cutting-block of new and novel design for use in conjunction therewith.

As at present practised, the so-called leather "Louis" heel of ladies' shoes is built up of superimposed layers, pieces or strips of leather of substantially the same size. It is necessary to cut or trim the inner edges of these pieces or strips in such superimposed relation, in order to obtain the proper, graceful curve required for a "Louis" heel. For this purpose, a heel breeding mechanism is employed the reciprocating cutter or knife of which in its forward movement impinges against a solid, wooden cutting-block. Much dissatisfaction results from this method because of the following facts: First, a wood cutting-block frequently, and in some instances in a single movement of the knife or cutter, splinters or crushes to such extent as to render the block useless for desired purposes and at the same time an imperfect heel is provided as a result of the splintering or crushing of said block. Second, a wood cutting-block requires frequent changes and is an item of considerable expense, both as to cost of block and loss of time in making the necessary change of block. Third, the reciprocating cutter or knife during its forward movement impinges against a cutting-block thus dulling the cutter or knife edge, with the result that frequent changes of cutters or knives for re-sharpening purposes is required. This procedure also consumes valuable time and is an added expense.

The principal object of the present invention is to overcome the above recited disadvantageous features and provide a rigid, shock-resisting cutting-block having formed in the working face thereof a cutter or knife edge receiving opening designed so that the cutting edge of a cutter or knife will not

contact with the edges of said opening. Other and further objects of the present invention reside in the providing of a more efficient, rapid and economical heel breeding mechanism than is now in general use.

With these and other objects in view, the invention consists of the improvements hereinafter described and finally claimed.

The nature, characteristic features and scope of the invention will be more fully understood from the following description taken in connection with the accompanying drawing forming part hereof and in which:

Figure 1, is a view in front elevation, of a heel breeding mechanism, equipped with a cutting-block embodying the invention;

Fig. 2, is a view in cross-section thereof;

Fig. 3, is a fragmentary view in plan of the cutting-block and holder therefor;

Fig. 4, is a front view of Fig. 3;

Fig. 5, is a perspective view of a cutting-block before assembling; and

Fig. 6, is a perspective view of a modified form of cutting-block.

For the purpose of illustrating my invention, I have shown in the accompanying drawings two forms thereof which are at present preferred by me, since the same have been found in practice to give satisfactory and reliable results, although it is to be understood that the various instrumentalities of which my invention consists can be variously arranged and organized and that my invention is not limited to the precise arrangement and organization of the instrumentalities as herein shown and described.

Referring to the drawings and more particularly to Figs. 1 and 2, there is illustrated a form of heel breeding mechanism suitable for use in conjunction with my specially designed cutting-block. Briefly stated, this mechanism is divided into a shoe positioning means and a cutting means. A description will be first given of the shoe positioning means. Rising from the bed-plate 10, of the machine are standards 11, 12 and 13. Connecting the standards 11 and 12, at the upper ends thereof is a cross-beam 14. Adjustably mounted, in any appropriate manner, for vertical movement with respect to the beam 14, is a heel-clamp 15, of angular cross-section, see Fig. 2.

Slidably mounted in the bed-plate 10, beneath the heel-clamp and arranged so as to be capable of being moved toward or away from said clamp, is a shoe support 16. The cutting means embraces a reciprocally mounted, horizontally disposed non-rotating shaft 17, the working end of which has clamped thereto a cutter or knife 18. This shaft is supported in bearings carried 10 by the standards 12, and 13, and is operatively disposed with respect to heel-clamp 15. Motion is imparted to said shaft by means of an eccentric and cam-follower connection 19, operable from a main driving shaft 20, through the intervention of bevel gearing 21. Releasable stop-mechanism 22^a, of any desired form is present to permit a complete reciprocation of the cutter or knife 18 for each two revolutions of 15 driving shaft 20. Carried by standard 11, opposite the knife or cutter just described and adjacent the heel-clamp 15, is a holder 22, for supporting in fixed position a cutting-block 23. As shown the holder if desired may be adjusted endwise as at 24, or 20 may be moved around a pivot connection 25. The cutting block 23, is disposed in the path of travel of the endwise movable knife or cutter 18, and receives the shock 25 or impact of the throw of the eccentric when the knife or cutter passes through a heel being breasted. The cutting-block I have designed is admirably fitted to meet this condition in that I employ a member 30 of rigid, shock-resisting material, preferably metal, and slot, groove or otherwise form in the working face of the block an opening to receive the cutting-edge of the knife or cutter at the end of its forward 35 stroke. The slot or groove is ample to receive said cutting-edge without the latter contacting in any way with the block. As shown in Figs. 3, 4 and 5, this cutting-block is of two sections 26 and 27. These 40 sections are so formed and proportioned that when assembled within the holder 22, and clamped thereto, as by bolts 28, there is disposed between the two sections a slot or groove 29. Obviously, depending upon 45 the particular shape of cutter or knife used, the specific formation of the adjacent faces of these sections vary in manufacture. In the present instance, the cutter is substantially J-shaped so that a substantially 50 J-shaped opening between the two sections is required. The general configuration of the cutting-block, however, is substantially rectangular with a generally curved, working face 30, and an offset 31, for one side. 55 The working face 30 of the cube-like cutting block is curved convexly to conform to the contour of the side of a shoe heel so that an efficient side support is afforded the heel. The rear portion of the cutting-block abuts against the front wall 32, of 60 65

the holder 22, and the offset 31, abuts against the front edge 33, of the holder 22. The end thrusts, shocks or impacts of the cutter or knife as it trims a shoe-heel are referred by the shoe to the shock resisting cutting block of the invention and as the block is rigidly clamped as aforesaid within the holder, there is no give to the cutting-block so that a clean cut of the cutter or knife is assured. 70

In Fig. 6, the cutting-block is formed of a one-piece casting 34, the working face of which is provided with a slot or groove 35. 75

The above described mechanism is particularly designed for the breasting of leather "Louis" heels for ladies' shoes. These heels are built up of superimposed pieces or strips of leather of the same relative size. At the proper time in the manufacture of a shoe, the shoe which has a last fitted therein is placed upon the shoe-support 16, in the position shown in Fig. 2, and the support is moved inwardly until the heel of the shoe abuts against the heel-clamp 15. The latter is then screwed down upon the heel. It is to be understood in this connection that so positioned the shoe itself abuts against the curved or working face 30, of the cutting-block 23. In operation one forward movement of the cutter or knife shapes the inner surface, of the heel by cutting away the edges of the various projecting strips. 80 85 90 95

It will now be apparent that I have devised a novel and useful construction which embodies the features of advantage enumerated as desirable in the statement of the invention and the above description and while I have in the present instance shown and described the preferred embodiment thereof which has been found in practice to give satisfactory and reliable results, it is to be understood that the same is susceptible of modification in various particulars without departing from the spirit or scope of the invention as claimed or sacrificing any of its advantages. 100 105 110 115

What I claim is:

1. A mechanism of the character stated embracing in combination a fixed substantially cube-like cutting block of rigid shock resisting material, the working face of which is convexly curved and conforms in contour to the side of a heel, said face having formed therein a knife edge receiving opening, a knife movable across the breast of a heel, the cutting edge of which is accommodated by the opening in said cutting block and means for clamping a heel in the path of travel of said knife. 120

2. As a new article of manufacture, a cutting block embracing a rigid shock-resisting substantially cube-like member, the working face of which is curved convexly to conform in contour to the side of a heel, 130

said face having formed therein a knife-edge receiving opening.

3. As a new article of manufacture, a cutting block embracing a rigid shock-resisting substantially cube-like member formed of separable sections adapted for fixed spaced relation to provide a knife receiving opening therebetween, the working face of

the combined sections being convexed to conform to the contour of the side of a heel. 10

In testimony whereof, I have hereunto signed my name.

ANDREW A. McINTYRE.
